UNITED STATES PATENT OFFICE

WILHELM ECKERT AND OTTO BRAUNSDORF, OF FRANKFORT-ON-THE-MAIN-HOCHST, GERMANY, ASSIGNEES TO GENERAL ANILINE WORKS, INC., OF NEW YORK, N. Y., A CORPORATION OF DELAWARE

NAPHTHOYLENE-ARYL-IMIDAZOL-PERI-DICARBOXYLIC ACID, A PROCESS OF PREPARING IT AND INTERMEDIATE PRODUCT OBTAINED DURING THIS PROCESS

No Drawing. Application filed May 29, 1929, Serial No. 367,113, and in Germany June 18, 1928.

The present invention relates to naphthoylene-aryl-imidazol-peri-dicarboxylic acids, a process of preparing them and intermediate products obtained during this process.

5 We have found that naphthoylene-aryl-imidazol-peri-mono- or di-alkyl indandions of the following general formula:

10 wherein R stands for an aromatic nucleus bound in two adjacent positions to the nitrogen atoms, which nucleus may contain substituents, X₁ for hydrogen or alkyl and X₂ for alkyl can easily be converted into the corresponding naphthoylene-aryl-imidazol-peri-dicarboxylic acids or anhydrides thereof.

20 The process is carried out in the following manner:

25 The said indandions are heated, advantageously to the boiling point, with concentrated aqueous alkali, whereby the following reaction takes place:

30 wherein R stands for an aromatic nucleus bound in two adjacent positions to the nitrogen atoms, which nucleus may contain sub-

40 gen atoms, which nucleus may contain substituents, X₁ for hydrogen or alkyl and X₂ for alkyl.

45 It is a surprising fact that while treating with strong alkali at boiling temperature the naphthoylene-aryl-imidazol ring is not likewise split up.

50 It is easy to obtain the naphthoylene-aryl-imidazol-peri-dicarboxylic acids from the above described intermediate products namely from the naphthoylene-aryl-imidazol-4(alkyl- or dialkyl acetyl)-5-carboxylic acids by treating them, advantageously in the presence of a solvent, with an oxidizing agent while gently heating on the water bath. As 55 oxidizing agents there may be used: potassium permanganate, sodium- or potassium bichromate chromic acid or the like. The solvent to be chosen depends on the oxidizing agents used; there can be applied: water, 60 caustic soda solution, glacial acetic acid, sulfuric acid or the like.

65 The new products thus obtained, namely the naphthoylene-aryl-imidazol-peri-dicarboxylic acids as well as the naphthoylene-aryl-imidazol-4(alkyl- or dialkyl-acetyl)-5-carboxylic acids formed as intermediate products have the following general formula:

70 wherein R₁ stands for the bivalent radical

75 in which R stands for an aromatic nucleus bound in two adjacent positions to the nitrogen atoms, which nucleus may contain sub-

stituents, Z for a hydroxy group or for an aliphatic group.

The new compounds are valuable intermediate products for the manufacture of dye-stuffs.

The above mentioned peri-dicarboxylic acids may also be obtained by condensing the acenaphthalic acid described by Freund and Fleischer (cf. Liebigs Annalen vol. 399, page 10 223) with ortho-diamines and subsequently oxidizing the condensation products in a suitable manner. It is very surprising that by this oxidation as well as by the above described oxidation process the naphthoylene-15 aryl-imidazol nucleus is not split up likewise.

The naphthoylene-aryl-imidazol-peri-mono-(or di-) alkyl indandions used as starting materials in our present process are obtainable by oxidation of the mono- (or di-) 20 alkyl-peri-indandions of acenaphthene (described by Freund and Fleischer in Liebigs Annalen vol. 373, page 324 and vol. 399, page 219) and subsequent condensation of the resulting naphthalene-4.5-mono-(or di-) alkyl-indandion-1.8-dicarboxylic acids and anhydrides respectively with ortho-diamines. The reaction takes the following course:

The following examples serve to illustrate our invention, but they are not intended to limit it thereto; the parts being by weight.

(1) The starting material used in this example is the naphthalene-4,5-diethyl-indandion-1,8-dicarboxylic acid or the anhydride thereof which easily may be obtained by oxidizing the acenaphthdiethyl-indandion with sodium bichromate in a solution of glacial acetic acid. When using sulfuric acid of between 35° and 45° Bé the reaction proceeds as well as when using glacial acetic acid. The anhydride crystallizes from glacial acetic acid in short, thick, faintly yellowish 50 prisms melting at between 168° C. and 170° C.

The condensation with ortho-phenylenediamine very easily takes place in a solution of glacial acetic acid and yields the naphthoylene-benzimidazol-peri-diethylindandion as 60 shining yellow crystalline laminae having a melting point of 254° C. to 256° C. It dissolves in concentrated sulfuric acid to a yellow solution without any fluorescence. The product can, furthermore, be reduced to a vat 65 by means of caustic soda solution and hydro-

sulfite and yields a greenish vat from which, however, it hardly dyes the cotton fiber.

One part of naphthoylene-benzimidazol-peri-diethyl-indandion of the following 70 probable formula:

thus obtained is introduced by and by, while stirring into a solution, heated to about 130°-150° C. of 8-10 parts of caustic potash and an equal quantity of water. The yellow starting material is quickly transformed into a dark-brown, granular mass, which for the most part floats on the surface of the strong lye. Heating is continued until a test portion taken from the mass dissolves in water to a dark yellow solution. The product is advantageously worked up by separating the caustic potash solution, heating the aqueous solution while passing air through it in order to precipitate at the same time the indandion which has not been split up but which has nevertheless been dissolved in the melt as 90 leuco compound by a reducing action, filtering by suction and precipitating with a dilute mineral acid. The naphthoylene-benzimidazol-4-diethyl-acetyl-5-carboxylic acid of the 95 following probable formula:

zol-peri-dicarboxylic acid is carried out as follows:

(a) 2 parts of naphthoylene-benzimidazol-4-diethylacetyl-5-carboxylic acid, obtained in the above described manner, are dissolved in an equivalent quantity of caustic soda solution of about 10% strength, while heating, and a solution of about 10% strength of about 5 parts of potassium permanganate is

10 gradually added at water-bath-temperature. The oxidation occurs rather rapidly while the solution assumes a green coloration; this green coloration, which is caused by intermediately formed potassium maganate, 15 finally disappears again, the potassium maganate splitting off manganese peroxide and thus having an after-oxidizing effect.

The solution, which is now yellow, is filtered from the manganese peroxide and 20 acidified. The naphthoylene-benzimidazol-peri-dicarboxylic acid separates as a reddish-yellow water-insoluble precipitate; it crystallizes from glacial acetic acid, in which it is rather difficultly soluble even while hot, in the 25 form of its anhydride as an orange yellow crystalline powder which assumes a yellow coloration when heated to 270° C. and which does not yet melt at 300° C. It dissolves in concentrated sulfuric acid to a faintly yellow 30 solution.

(b) 10 parts of the crude product of naphthoylene-benzimidazol-4-diethylacetyl-5-carboxylic acid are dissolved by heating in 8-10 times their weight of glacial acetic acid and 35 30-35 parts of sodiumbichromate are slowly added while the solution is gently kept at boiling temperature. A solution of the oxidizing agent in glacial acetic acid may also be added drop by drop. After a short 40 time already the oxidation product which is only very difficultly soluble in glacial acetic acid begins to precipitate in the form of small yellow little-crystals. After the reaction is finished, the crystals are introduced 45 into diluted sulfuric acid, the liquid is filtered with suction and the crystals are freed from the chromate by washing them with water. By boiling with glacial acetic acid there is from the crude product the 50 naphthoylene-benzimidazol-peri-dicarboxylic anhydride in a pure state as an orange yellow crystalline powder which scarcely dissolves in organic solvents. It has the same properties as described under (a). The melting point of the pure product lies still above 350° C. The contents of nitrogen were determined 8.03%, the contents of the acid $C_{20}H_{10}O_5N_2$ were calculated 7.82% and the contents of its anhydride $C_{20}H_8O_4N_2$ 8.23%.

55 When starting instead of from the naphthoylene-benzimidazol-peri-diethylindandion mentioned in Example 1 from indandions the benzene nucleus of which is substituted or replaced by another hydrocarbon residue or from indandions having instead

of the ethyl group a methyl group or the like, the corresponding carboxylic acids or their anhydrides are obtained.

(2) Into a melt of 500 parts of caustic potash and 150 parts of water are introduced, 70 while stirring, 50 parts of naphthoylene-chloro-benzimidazol-peri-diethylindandion of the following probable formula:

75 obtainable by condensing naphthalene-4,5-diethylindandion-1,8-dicarboxylic acid or its anhydride, with 4-chloro-1,2-diaminobenzene. The temperature of the molten mass is gradually raised to about 180° C. and maintained there until a test portion dissolved in water only yields a minute precipitate of unaltered indandion when being thoroughly shaken with air.

90 The reaction product is isolated as indicated in Example 1. It is a brownish-yellow amorphous substance, rather easily soluble 100 in organic solvents such as glacial acetic acid, ethyl alcohol or acetone more difficultly soluble in benzene. It dissolves in concentrated sulfuric acid to reddish-yellow solution. The acid is readily soluble to a yellow 105 solution in sodium carbonate solution, diluted alkalis or dilute aqueous ammonia.

110 10 parts of naphthoylene-chloro-benzimidazol-4-diethyl-acetyl-5-carboxylic acid of the following probable formula:

115 thus obtained are dissolved in 10 times their weight of glacial acetic acid while heating and 40 parts of sodium bichromate, dissolved 120 in glacial acetic acid, are introduced gradually at a temperature of between 80° C. and 130

90° C. After the oxidation is finished, the solution is given into water, acidified subsequently with sulfuric acid, boiled, the yellow precipitate is filtered with suction and rinsed with water. It consists for the most part of the anhydride of the naphthoylene-chlorobenzimidazol-peri-dicarboxylic acid of the following probable formula:

20 by boiling with glacial acetic acid the anhydride can be obtained in a pure state as a yellow powder extremely difficultly soluble in organic solvents. It dissolves in concentrated sulfuric acid to a faintly yellow solution.

25 We claim:

1. The process which comprises heating a compound of the following formula:

45 wherein R stands for a bivalent aromatic radical of the benzene series bound in ortho-positions to the nitrogen atoms, X₁ for hydrogen or alkyl, X₂ for alkyl, with a concentrated aqueous alkali and treating the intermediate product thus obtained with an oxidizing agent in the presence of a diluent while gently heating.

50 2. The process which comprises heating to boiling temperature a compound of the following formula:

65 wherein R stands for a bivalent aromatic radical of the benzene series bound in oth-

positions to the nitrogen atoms, X₁ for hydrogen or alkyl and X₂ for alkyl, with concentrated aqueous caustic potash and treating the intermediate product thus obtained with sodium bichromate in the presence of 70 acetic anhydride.

3. The process which comprises heating a compound of the following formula:

wherein Y stands for hydrogen or chlorine, X₁ for hydrogen or alkyl and X₂ for alkyl, with concentrated aqueous alkali and treating the intermediate product thus obtained with an oxidizing agent in the presence of a diluent while gently heating.

4. The process which comprises heating to 95 boiling temperature a compound of the following formula:

110 wherein Y stands for hydrogen or chlorine, X₁ for hydrogen or alkyl and X₂ for alkyl, with concentrated aqueous caustic potash and treating the intermediate product thus obtained with sodium bichromate in the presence of acetic anhydride.

5. The process which comprises heating naphthoylene - benzimidazol - peri - diethyl-indandion with concentrated aqueous alkali and treating the intermediate product thus obtained with an oxidizing agent in the presence of a diluent while gently heating.

6. The process which comprises heating to 125 boiling temperature naphthoylene-benzimidazol-peri-diethyl-indandion with concentrated aqueous caustic potash and treating the intermediate product thus obtained with sodium bichromate in the presence of glacial acetic anhydride.

7. As new products, compounds of the following formula:

Z stands for a hydroxy group or for the radical:

10 wherein R₁ stands for the bivalent radical:

20 in which R stands for a bivalent aromatic radical of the benzene series bound in ortho-positions to the nitrogen atoms, Z for a hydroxi group or for the group

25 X₁ being hydrogen or alkyl, X₂ being alkyl.

8. As new products, compounds of the following formula:

35 wherein R₁ stands for the bivalent radical:

45 Y for hydrogen or chlorine, Z for a hydroxi group or for the group

50 X₁ being hydrogen or alkyl, X₂ being alkyl.

9. As new products, compounds of the following formula:

60 wherein R₁ stands for the bivalent radical:

10. As a new product, naphthoyle-benzimidazol-peri-dicarboxylic acid being a reddish-yellow product which crystallizes from glacial acetic acid in form of its anhydride 75 as an orange-yellow crystalline powder melting at a temperature about 350° C. and dissolving in concentrated sulfuric acid to a faintly yellow solution.

11. As a new product, naphthoyle-chloro-benzimidazole-peri-dicarboxylic acid 80 of the following probable formula:

90 being a yellow powder which is converted 95 into its anhydride by boiling it with glacial acetic acid.

In testimony whereof, we affix our signatures.
